CLAIM

The ornamental design for handle for a spoon or similar article of flatware, substantially as shown and described.

DESCRIPTION

FIG. 1 is a top plan view of a handle for a spoon or similar article of flatware showing my new design, the broken line showing of a spoon bowl being illustrative of environmental matter only and forms no part of the claimed design.

FIG. 2 is a view from the left side of FIG. 1, the opposite side being a mirror image thereof;

FIG. 3 is a bottom plan view thereof;

FIG. 4 is a sectional view taken along line IV—IV of FIG. 1; and

FIG. 5 is a sectional view taken along line V—V of FIG. 1.

FIG. 1

FIG. 2

FIG. 3

FIG. 4

FIG. 5
